UNITED STATES PATENT OFFICE.

MICHAEL C. ARMOUR, OF CHICAGO, ILLINOIS.

STOVE.

SPECIFICATION forming part of Letters Patent No. 273,005, dated February 27, 1883.

Application filed February 20, 1882. (No model.)

To all whom it may concern:

Be it known that I, MICHAEL C. ARMOUR, a citizen of the United States, residing at Chicago, in the county of Cook and State of Illinois, have invented certain new and useful Improvements in Stoves, which are set forth in the following specification, reference being had to the accompanying drawings, in which—

Figure 1 is a plan view of a stove embodying my improvements; Fig. 2, a longitudinal section of the same on the line *x x* of Fig. 1; Fig. 3, a plan section of the same on the line *y y* of Fig. 2; Fig. 4, a transverse section of the same on the line *z z* of Fig. 2; Fig. 5, a front elevation of the stove on a small scale; Fig. 6, a detail view of the stove-top, showing an arrangement of the covering-plates by which the heat is all directed to one of the vessel-openings; Fig. 7, a detail section taken on the line *v v* of Fig. 6, showing the position of the damper-flanges of the covering-plates; Fig. 8, a detail longitudinal section of the upper part of the stove, showing the damper-flange of one of the covering-plates placed between the tops 25 of the two chimneys to positively keep separate the respective combustion-currents arising therefrom; Fig. 9, a detail perspective view of one of the covering-plates with its damper-flange; Fig. 10, a plan view of the lamp, and Fig. 11 a transverse section of the upper part of the lamp, showing the draft-passages and deflecting-plates.

My invention relates to stoves in which oil or gas is the fuel used.

My invention consists, first, of a stove provided with a chamber containing various constituent parts of a combustion apparatus, which parts are separable from each other and from the rest of the stove; second, of details of construction facilitating the adjustment of these separable parts; third, of means for preventing a precipitate flow of air to the burners; and, fourth, of means for directing and preserving the combustion-current.

In the drawings, A represents an oven heated by radiation. B is a lamp-chamber separated from said oven by a partition-plate, C, and from the chimney-chamber F by a plate, D, the latter plate resting removably upon 50 cleats *d*, secured to the former and to the outer

wall of the stove, and being guided in sliding in and out by fitting closely between the partition C and said outer wall. E is a plate held apart from and secured to the plate D by the rods *e*.

Depending from the plate D are the cones G, and above, between it and the plate E, are adjusted the chimneys F, which slide in and out between the guides *f*, and for which openings are provided in the plate E. It will be seen from the above that the cones and their respective chimneys form flues, and that the plates D and E, connected by the rods *e*, form a chimney-frame, which readily slides into and out of place by the means just specified as adapted for the plate D. The cones reach down to the level of the air-box K' of the lamp K, as shown, and have end apertures, which admit of the entrance under them of the burners H (which are the upper ends of the wick-tubes) when the lamp is made to slide in under the cones, and which are closed, when the lamp reaches its proper place under the cones, by the upright studs or plates J, rising from the top of the lamp, and of such size and shape as to enter and closely fill said end apertures. The sliding of the lamp is directed by the guides *i* and *i'*.

As the chimneys and chimney-frame are within the chimney-chamber F', the door L' is provided, which opens to admit of the insertion and removal of said chimneys and chimney-frame. This door L' is provided with mica windows, *l*, and opposite these are similar ones in the chimneys for the purpose of observing the condition of combustion and for the emission of light.

L is the oven-door.

The air-box K' is supported at a distance above the oil-reservoir *k* on pedestals or stands in order to keep the oil-reservoir cool. The air-box is provided with draft-deflecting plates *k'*, each of which, with a plate, *k*², forms an air-passage. The air-box is also provided with plates *k*³ and *k*⁴, which also form air-passages. All of these plates within the air-box extend in the direction of the long dimension of the cones and burners entirely across the air box. In the transverse direction, however, the plates *k*² and *k*⁴ do not quite reach the roc

wick-tubes, thus leaving each wick-tube surrounded by an orifice, k^5 , through which air can approach the flame from all sides of the wick-tubes; and the deflecting-plates k' at their curved ends do not quite reach to the outer wall of the air-box, thus leaving an air-orifice, k^6 . Below this orifice k^6 is an orifice, k^7 , in the wall of the air-box. The plate k^8 has orifices k^8 , and immediately under these is an orifice, k^9 , in the bottom of the air-box. The end of the plate k' is curved, as shown, in order that when a sudden gust of wind enters the orifice k^7 it will pass in beyond the orifice k^6 , return above its inward path until it strikes the curved end of the plate k' , and be deflected by said curved end against and into the incoming current, the result of which collision is that an eddy is created, the collision of the two currents forming a resultant current flowing away from rather than toward the orifice k^6 , and ultimately traversing the eddying path just described for the gust when first entering the box. Precipitation in the approach to the burners of so much of the air as, notwithstanding these precautions, enters the orifice k^6 is still further impeded by the sharp angles which must be encountered by the draft thereafter, as shown in the drawings. The air entering through the orifice k^9 is likewise impeded by the tortuousness of its course. The courses of the drafts through the air-box are shown by arrows in the drawings.

Above the oven and chimney-chamber is a chamber, M, open on top and at each end. This chamber is covered when in use by one or more of the covering-plates N, O, and P. Each of these plates N O P has a depending flange, n , on one side, as shown in Fig. 9, which may be termed a "damper-flange," and which is set a little back from the edge of the plate to allow the latter to rest on the parallel rabbed tops m of the vertical sides of the chamber M. The plates N and O have vessel openings and covers Q, and the plate P has grooves p across its upper face, the upper edges of which grooves are higher than the upper surfaces of the other covering-plates and than the tops of the vertical sides of the chamber M, and the bottoms of which grooves are perforated with holes p' , all as shown, for the purpose (which it will serve in some arrangements of the covering-plates) of providing an escape for the products of combustion in case of the accidental closing of all other outlets, the upper edges of the grooves being higher than other parts adjacent to the plate P in order to afford an exit for the combustion-current between such adjacent parts and any cooking-vessel accidentally allowed to cover all or nearly all the perforations through the bottoms of the grooves.

The operation of my invention so far as it has not already been specified is as follows: The chimneys, alone or with the chimney-frame, may be removed from their position in the stove by simply opening the door L'. The lamp may be removed without opening the

door L' or removing either the chimney-frame or chimneys, though, when desirable, both the chimneys and the chimney-frame may be removed as one piece with the lamp. The covering-plates, being square, can each be set on the stove in any one of four positions, thus rendering possible a variety of positions of the damper-flanges. Thus, in ordinary use, the covering-plates will frequently be set on with the flanges at the back side of the stove, as shown in Fig. 4, where they are inoperative, leaving a free passage entirely through the chamber M, from each end of which the products of combustion will ordinarily be discharged; but when it is desired to positively divide, or rather keep separate, the draft arising from one chimney from that arising from the other, (as may be necessary in case of strong drafts tending to enter the end of the chamber M,) one of the covering-plates is raised and turned around so as to drop its flange between the tops of the chimneys, it being understood that all the damper-flanges are of such a length and depth as, when thus used, to extend entirely across the chamber M both laterally and vertically. This disposition of the covering-plates and damper-flanges is shown in Fig. 8, where the plate O has its damper-flange across the chamber M. Again, it may sometimes be desired to direct the currents from both chimneys through the vessel-opening of a single covering-plate. In such case one of the covering-plates is removed and the other two plates are placed with their flanges across the chamber M, as shown in Fig. 7, both chimney-tops being between the two damper-flanges. By making the rabbeted tops of the sides of the chamber M parallel the positions of the covering-plates may, both as to their flanges and as to the chamber M, be readily varied. The lamp, chimney frame, chimneys, and cones are removable without disturbing the stove proper, this being accomplished by supporting the latter independently of the former by means of the walls of their containing-chamber. By making the cones below the plate D the chimneys can be supported by said plate, and can be removed therefrom without interference from the cones projecting up into said chimneys.

Having thus described my invention, what I claim as new, and desire to secure by Letters Patent, is—

1. In an oil or gas stove, a removable chimney-support, in combination with a chimney adapted to slide horizontally in and out from the support, substantially as and for the purpose described.

2. In an oil or gas stove, an outer casing, in combination with a separate horizontal plate resting on ways arranged within the casing, and with separate chimneys resting in ways on the plate, the casing being provided with a doorway large enough to allow the passage of the plate and chimneys, substantially as and for the purpose described.

3. In an oil-stove, the plate D, having the

cones of the burners depending from it, so as to be entirely below it, and having apertures registering with the cones, substantially as and for the purpose described.

5. 4. In an oil or gas stove, the plate D, cones entirely below the same, and chimneys resting upon and removable from the same, combined and operating substantially as set forth.

5. In an oil or gas stove, flues provided with 10 apertures to receive the burners, and a lamp provided with studs for closing said apertures, combined and operating substantially as set forth.

6. In an oil or gas stove, the combination 15 of the bottom of the air-box, with the plate k', having a curved end, and the sides of the air-box K', provided with the orifice k', substantially as and for the purpose set forth.

7. In an oil or gas stove, an upper chamber, 20 M, open at the top, having parallel sides and a series of apertures in its floor corresponding to the tops of the chimneys, in combination with square covering-plates, each equal in

breadth to the chamber and provided with a depending vertical flange along one of its 25 edges, substantially as and for the purpose described.

8. In an oil or gas stove, a chamber, M, having parallel rests for a covering-plate, and a covering-plate provided with a damper-flange 30 insertible within said chamber M, substantially as set forth.

9. In an oil or gas stove, a series of chimneys, in combination with covering-plates, each provided with a damper-flange depending to 35 a position between two chimneys, substantially as and for the purpose described.

10. In an oil or gas stove, in combination with the burners, the corrugated and perforated top P, substantially as and for the pur- 40 pose described.
